Primary Examiner — Cynthia M Chin*(74) Attorney, Agent, or Firm* — Mayback & Hoffman, P.A.;
Gregory L. Mayback(57) **CLAIM**

The ornamental design for a handle, as shown and described.

DESCRIPTION

FIG. 1 is a perspective view of a handle showing my new design;

FIG. 2 is an elevational view of a left side of the handle of FIG. 1;

FIG. 3 is an elevational view of a right side of the handle of FIG. 1 from a side opposite the view of FIG. 2;

FIG. 4 is an elevational view of a front side of the handle of FIG. 1;

FIG. 5 is an elevational view of a rear side of the handle of FIG. 1 from a side opposite the view of FIG. 4;

FIG. 6 is a top plan view of the handle of FIG. 1; and,

FIG. 7 is a bottom plan view of the handle of FIG. 1.

The dashed lines indicating holes are for the purpose of illustrating unclaimed environment of the design, are for illustrative purposes only, and form no part of the claimed design.
